(57) CLAIM

The ornamental design for an inflatable gaga court, as shown and described.

DESCRIPTION

FIG. 1 is a front, left, and top perspective view of the inflatable gaga court, showing my new design;

FIG. 2 is a front, right, and top perspective view thereof;

FIG. 3 is a rear, right, and bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an enlarged view of the area labeled 10 in FIG. 1.

The dashed lines in the figures illustrate portions of the inflatable gaga court that form no part of the claimed design. The dash dot dash broken lines of the inflatable gaga court in FIG. 1 illustrate a boundary and cut line of the enlarged view in FIG. 10 and form no part of the claimed design.

1 Claim, 10 Drawing Sheets
